Primary Examiner — Xavier Marti-Santos(74) *Attorney, Agent, or Firm* — ANOVA LAW GROUP, PLLC(57) **CLAIM**

The ornamental design for a curling iron, as shown and described.

DESCRIPTION

FIG. 1 is a front elevational view of a curling iron in accordance with the present disclosure.

FIG. 2 is a left side elevational view of the curling iron in accordance with the present disclosure.

FIG. 3 is a right side elevational view of the curling iron in accordance with the present disclosure.

FIG. 4 is a rear elevational view of the curling iron in accordance with the present disclosure.

FIG. 5 is a bottom elevational view of the curling iron in accordance with the present disclosure.

FIG. 6 is a top elevational view of the curling iron in accordance with the present disclosure.

FIG. 7 is a front and right side perspective view of the curling iron in accordance with the present disclosure; and, FIG. 8 is a rear and right side perspective view of the curling iron in accordance with the present disclosure.

The broken lines in the specification are for the purposes of illustrating portions of the curling iron, which form no part of the claim design.
